UNITED STATES PATENT OFFICE.

GILES S. MOORE, OF INDIANAPOLIS, INDIANA, ASSIGNOR TO TROLLEY SHOE-WHEEL COMPANY, OF INDIANAPOLIS, INDIANA, A CORPORATION OF INDIANA.

TROLLEY WHEEL.

Application filed May 31, 1923. Serial No. 642,570.

To all whom it may concern:

Be it known that I, GILES S. Moore, a citizen of the United States, residing at Indianapolis, in the county of Marion and State of Indiana, have invented certain new and useful Improvements in Trolley Wheels, of which the following is a specification.

My said invention relates to a trolley having a sliding contact shoe for engaging the wire during the ordinary operation while the trolley is moving in a forward direction together with the car by which it is carried. Such a sliding contact shoe has been found to have many advantages over the ordinary trolley wheels. Some of these advantages are that the damage to the wire due to arcing is lessened as arcing takes place to much less extent with a shoe than with a wheel, less current is lost due to such arcing, the shoe needs no greasing, the parts need not be renewed as often as in the case of wheels, there is a more steady flow of current to the car and less resistance to overcome between the wire and the car, less current is wasted in winter due to frost and sleet and less damage is done to the wire. Since it is not necessary to oil the shoe the danger incident to walking over the roof of the car for this purpose in cold weather is done away with, as well as the damage done to the car roofs by walking on them. There is less vibration, the lights are more steady and the car rides more evenly and with greater comfort to passengers. There is also less expense of wear and maintenance in various respects and owing to various circumstances such as that the shoe does not collect copper from the wire, does not wear ears in overhead construction and does not crystallize the wire in spots as a wheel does thereby causing the wire to break. Many other advantages could be stated but the above are believed to provide a sufficient illustration of the importance of this development in trolley construction.

Referring to the accompanying drawings, which are made a part hereof and on which similar reference characters indicate similar parts,

Figure 1 is a side elevation of my device partly in section, with the trolley moving in the direction of the arrow, i. e. in a forward direction,

Figure 2, a similar view showing the trolley moving in the opposite direction, i. e. in a rearward direction, and

Figure 3, a section on line 3—3 of Figure 1.

In the drawings reference character 10 indicates a harp supported on a pole as is usual and having forks 11 which are connected at the upper end by a bolt 12 forming a pivot for a bracket 13. The bracket carries a shoe 14 at the end which is normally uppermost, this shoe being made of sheet metal or other convenient material and having upstanding flanges 15 at opposite sides curving outward at their upper extremities. A removable wear plate 16 is located on the shoe between the flanges 15 and is bent downward at its front end to cause its under surface to correspond to the upper face of the curved part 17 of the shoe. At the other end the shoe terminates abruptly and the wear plate has a depending flange or shoulder 18, the forward face of which engages the rear end of the shoe while the rearward face extends substantially in a common plane with the axis of a bolt 19 carried between forks at the normally lowermost end of the bracket 13. Any conventional or desirable anti-friction and lubricating devices may be provided in connection with the pivot 19 but they form no part of my invention and so are omitted from the drawings. The conformation of the contacting parts of the shoe and the wear plate serves to fit them accurately to each other whereby also the plate will be held in place on the shoe. I provide also for a positive connection between the parts by forming a threaded opening in the wear plate for engagement by a screw 20, the head of which is located in a counter-sunk opening in the shoe. The shape of the contacting faces of the shoe and plate insures that the holes in the two parts will register when the parts are fitted together.

The pivot 19 between the forks of the bracket, which bracket is here shown as forked at each end and integral in the middle but which may consist of two separate side pieces if preferred, provides means for rotatably supporting a trolley wheel 21 which is flanged as usual at 22 and is so positioned relatively to the shoe that the flange 18 on

the shoe enters between the flanges 22 on the wheel. This insures against any displacement of the wheel relatively to the shoe such as might cause disengagement of the 5 trolley from the wire as it passes from one element to the other.

A cross bar 24 is provided between the forks of the harp, this cross-bar being engaged in one position of the bracket 13 by 10 the flanges of the wheel 21 and in the other extreme position by the under or rear face of the shoe 14. The cross-bar 24 may obviously be replaced by lugs on the two forks of the harp or by a single lug or any equivalent construction.

In the operation of the device it will be evident that the sliding shoe will contact with the trolley wire whenever the trolley 20 is moving forward whereas when the car begins to move in reverse direction the bracket will tilt and cause the wheel to come in contact with the wire. At such times the bar 24 will act as a stop to limit the tilting movement of the bracket whereby the 25 wheel will engage the wire in the position shown in Figure 2. When the rearward movement of the car is again changed to a forward movement the resistance between the wheel and the wire together with the 30 action of gravity will cause the bracket to tilt thereby moving the wheel toward the position shown in Figure 1, the shoe also moving toward the position there shown. The friction between the wheel and the rear 35 end of the shoe on the one hand and the wire on the other hand augments this tendency and hastens the tilting action.

It will be seen that when the wear plate 40 becomes worn another plate can readily be inserted in its place and because of the structure illustrated and described this will be a very simple matter requiring but little time to locate the wear plate relatively to the shoe. It will also be noted that the 45 bar 24 acts as a stop to limit the movement of the bracket toward the position of Figure 1 and that it may exert a braking action on the wheel to stop its rotation at this time. The wheel is here shown as having a plain surface but I contemplate applying removable tread sections thereto in some such manner as that described in Patent No. 1,382,664, of June 28, 1921 to Otto Moore.

50 It will be obvious to those skilled in the art that many changes may be made in the details of construction of my device without departing from the spirit of the invention and therefore I do not limit myself to the construction shown in the draw-

ings and described in the specification but only as indicated in the appended claims.

Having thus fully described my said invention, what I claim as new and desire to secure by Letters Patent, is:

1. In a trolley, a harp, a bracket pivoted to the harp, a member on the bracket arranged to have sliding contact with the wire during movement of the device in one direction, and a wheel on the bracket arranged to engage the wire on movement in the opposite direction, said sliding contact member at its rear end sloping abruptly toward said wheel and the axis of the wheel being normally directly beneath said rear end, substantially as set forth.

2. In a trolley, a harp, a bracket pivoted to the harp, a member on the bracket arranged to have sliding contact with the wire during movement of the device in one direction, and a wheel on the bracket arranged to engage the wire on movement in the opposite direction the flattened rear end of the sliding contact member lying in a plane passing approximately through the axis of said wheel, substantially as set forth.

3. In a trolley, a harp, a bracket pivotally supported on the harp, a shoe fixed to the bracket, a wheel pivotally supported by the bracket, and common means on the harp for engagement by the bracket and the wheel to limit the movement of the bracket in either direction, substantially as set forth.

4. In a trolley, a harp, a bracket pivotally supported on the harp, a shoe fixed to the bracket, a wheel pivotally supported by the bracket, and a cross-bar between the forks of the harp engageable alternately by the shoe and the wheel for limiting the movement of the bracket, substantially as set forth.

5. In a trolley, a sliding contact shoe, a removable wear plate, means for securing the plate on the shoe, means for accurately positioning the plate on the shoe, similarly curved surfaces at one end of said members, a flange at the other end of one member adapted to abut against the adjacent end of the other, and means to fasten the members in such relation, substantially as set forth.

In witness whereof, I have hereunto set my hand and seal at Indianapolis, Indiana this 29th day of May, A. D. nineteen hundred and twenty-three.

GILES S. MOORE. [L. s.]
